(57) **CLAIM**

The ornamental design for a bracelet, as shown and described.

DESCRIPTION

FIG. 1 is a top front perspective view of a bracelet according to my new and ornamental design;

FIG. 2 is a top rear perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a bottom front perspective view thereof;

FIG. 10 is a bottom rear perspective view thereof;

FIG. 11 is an enlarged view of the area noted in FIG. 2; and,

(Continued)

FIG. 12 is a top plan view of the bracelet in an alternative, unclasped and open position.

The broken lines shown representing an enlarged section of the claimed design illustrate the bounds of the area for enlargement and form no part of the claimed design.
